VISOR FOR AUTOMOBILE HEADLIGHTS

Clifford Myers, Cleveland, Ohio

Application January 5, 1950, Serial No. 7,011

Term of patent 3½ years

(Cl. D48—32)

To all whom it may concern:

Be it known that I, Clifford Myers, a citizen of the United States, residing in the city of Cleveland, county of Cuyahoga, and State of Ohio, have invented a new, original, and ornamental Design for a Visor for Automobile Headlights, of which the following is a specification, reference being had to the accompanying drawing, forming a part hereof, in which:

Figure 1 is a side elevational view of a visor for automobile headlights, showing my new design;

Figure 2 is a front elevational view thereof;
Figure 3 is a cross-sectional view taken on the line 3—3 of Figure 2;

Figure 4 is a top plan view; and
Figure 5 is a bottom plan view.

The broken lines shown in the drawing are for the purpose of illustration only.

I claim:

The ornamental design for a visor for automobile headlights, substantially as shown and described.

CLIFFORD MYERS.
